(57) **CLAIM**

The ornamental Design for a chair, as shown and described.

DESCRIPTION

FIG. 1 is a perspective view from the front of the chair showing my new design.

FIG. 2 is a front elevational view of the chair of FIG. 1.

FIG. 3 is a side elevational view of the chair of FIG. 1. The other side is a mirror image of this view.

FIG. 4 is a rear elevational view of the chair of FIG. 1; and, FIG. 5 is a top plan view of the chair of FIG. 1.

The broken line showing of the base of the chair is for illustrative purposes only and forms no part of the claimed design.

1 Claim, 3 Drawing SheetsFIG. 1.

FIG. 2.

FIG. 5.
